UNITED STATES PATENT OFFICE.

GEORGE H. BENTON, OF BOONTON, NEW JERSEY.

DESIGN FOR A PAPER-WEIGHT.

SPECIFICATION forming part of Design No. 18,936, dated February 26, 1889.

Application filed January 10, 1889. Serial No. 295,989. Term of patent 7 years.

To all whom it may concern:

Be it known that I, GEORGE H. BENTON, a citizen of the United States, residing at Boonton, in the county of Morris and State of New Jersey, have invented and produced a new and original Design for a Paper-Weight, of which the following is a specification.

The object of this invention is to provide a novel and attractive paper-weight, and the 10 leading feature thereof consists in a base-plate surmounted by the representation of a valve-casing comprising branches and a projecting neck.

The invention is illustrated by the accompanying drawing, in which the figure is a side elevation.

In the drawing, the letter A indicates a base-plate surmounted by the representation of a valve-casing, B, which, as shown, comprises 20 two branches, C C, having end collars which

are polygonal, and a central vertically-projecting ornamental neck, F, that has an ornamental polygonal collar, G, on its upper portion. A stem, D, rises from the neck, provided with a handle, E. The sides of the 25 base-plate are beveled or inclined and its under side is flattened.

What I claim is—

The design for a paper-weight, consisting of a base-plate surmounted by a representation 30 of a valve-casing comprising branches and a projecting neck, substantially as shown and described.

In testimony whereof I affix my signature in presence of two witnesses.

GEORGE H. BENTON.
